UNITED STATES PATENT OFFICE.

DAVID C. KLAUSMEYER, OF CINCINNATI, OHIO, ASSIGNOR TO THE CINCINNATI BICKFORD TOOL COMPANY, OF CINCINNATI, OHIO, A CORPORATION OF OHIO.

COLUMN-CLAMPING MECHANISM.

Application filed September 6, 1921. Serial No. 498,634.

To all whom it may concern:

Be it known that I, DAVID C. KLAUSMEYER, a citizen of the United States, and residing at Cincinnati, in the county of Hamilton and State of Ohio, have invented a new and Improved Column-Clamping Mechanism, of which the following specification is a full disclosure.

This invention relates to clamping mechanisms for radial-drills and it is primarily concerned with the proposition of rendering conveniently accessible to the user the means for manually operating the clamp which locks the radial arm against swinging in a horizontal plane.

In radial-drills, it is customary to mount the drill-head on an arm that horizontally projects from an upright post or column; the mounting of the arm being of such a nature that it may be raised and lowered and may also be swung laterally with respect to its vertical axis. For this purpose, an upright sleeve is pivoted about the post and one end of the arm circumscribes the sleeve and is adapted to slide vertically thereon but not to rotate relative to the sleeve. The vertical slide of the arm is restricted by means of clamping-levers mounted on its circumscribing end, and heretofore the lateral swing of the arm has been restricted by means of a clamp located at the base of the sleeve and adapted to be operated to clamp the sleeve against rotation about the post. It is quite inconvenient for the user to leave the work and to go to the base of the sleeve for the purpose of operating the sleeve-clamp and this invention proposes to rectify this condition by arranging the sleeve clamp-lever in the immediate vicinity of the clamp-levers employed for restricting the vertical slide of the arm. It, furthermore, proposes for the clamp-lever and for its connection with the sleeve clamp, a mounting so designed that the clamp-lever will remain in a constant position relative to the clamp-levers for the arm, so that the user will always find the clamp-levers clustered together in the same relation irrespective of either the vertical or the lateral shift in the position of the arm.

Other objects and advantages will be in part indicated in the following description and in part rendered apparent therefrom in connection with the annexed drawings.

To enable others skilled in the art so fully

to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Fig. 1 is a side elevation of a radial-drill embodying this invention. Fig. 2 is a fragmentary rear elevation of the same showing in section the clamp surfaces between the sleeve and the post. Fig. 3 is a section through line 3—3 of Fig. 2 showing the concentric relation between the sleeve-like end of the arm, the upright sleeve and the post and showing also in plan the clamping-levers for the arm and the sleeve respectively. Fig. 4 is a detail of the end of the sleeve clamp-lever. Fig. 5 is a front view of the part shown by Fig. 4. Fig. 6 is a fragmentary section of the turn-shaft for the sleeve-clamp showing an end view of the collar splined to the shaft and to which the clamp-lever is pinned. Fig. 7 is a side elevation of the parts shown in Fig. 6. Fig. 8 is a fragmentary detail of the clamp for the sleeve.

Referring to the drawings, A indicates the base of the machine on which is bolted the lower end A' of the post A² which extends upwardly and rotatably supports the sleeve B in a conventional manner. The lower end of this sleeve is enlarged bell-like, as indicated by B', so as to provide a portion circumscribing the braking surface A² presented by the lower portion of the post. The bell B' of the sleeve has a circumferential cut 1 and a transverse cut 2; thereby providing short flexible wings e and a which may be constricted by means of a draw-bolt 5 adapted to squeeze together the lugs a' and e' integrally formed on said wings. This draw-bolt 5 terminates at one end in an eye 7 circumscribing an eccentric 4 formed on a shaft 3 journaled at its ends in the lug a'. The other end of the bolt 5 carries lock-nuts 6 for adjusting its initial tension and, as will be seen, a rotation of the shaft 3 will effect a clamping of the sleeve on the braking surface A².

Unlike the conventional arrangement, the aforesaid clamp is not operated by a lever mounted on the base of the sleeve or located adjacent its lower end, but is, in accordance

with this invention, operated by a lever that is mounted on the circumscribing portion of the arm and which is carried thereby so as to be always located in proximity with the clamp-levers which restrict the vertical shift of the arm. Thus, R indicates a lever journaled in a bearing 10 projecting from the sleeve-like portion M' of the arm M. This lever is in splined relation with a shaft C' 10 which is used as an extension of the shaft 3; it being affixed to the latter by any suitable coupling C'. The splined relation between the lever R and the shaft C may advantageously be established through a small 15 sleeve such as that indicated by P in Fig. 7. This construction provides an extensible connection whereby the lever R is operatively connected to the sleeve-clamp in all of the positions of the arm M on the sleeve B. 20 This small sleeve provides a bearing surface 11 which is journaled in the bearing 10 and is restrained from end-wise movement by its shoulder 12. The lever R has an annular portion r apertured to fit snugly on 25 the upper end of the sleeve P and locked against end-wise movement by means of a pin 17 (see Fig. 1) passing through the aperture 16 in the lever and interfitting with the notch 15 in the upper end of the sleeve 30 P. To secure the lever R against rotating relative to the sleeve P, it is provided with a key 14 interfitting with the key-way 13 in the sleeve. The shaft C has a splined groove throughout its length and the sleeve 35 P has its bore provided with a spline 11 secured thereto and riding in the groove in the shaft C. By this means, the user is enabled to operate the clamp by grasping the end of the lever R which is sufficiently 40 long to be quite accessible to him. In order, however, to prevent the lever R from swinging too far when operating the sleeve clamp, it is preferably provided with the projecting lug 18 which, as shown by Fig. 3, will 45 impact the adjacent portion of the arm and restrict any undue movement of the lever R.

Inasmuch as the shaft C is journaled at its upper and lower ends, respectively, in lugs 3 and 9, it will be seen that such shaft 50 is carried bodily around with the sleeve B when the arm is being adjusted laterally. The lug 9 is an integral part of the head B² which in turn is in unitary relation with the sleeve B. This head also provides a 55 journaled 19 for a lifting-screw H which is likewise journaled in a bearing 20 provided by the lower end B' of the sleeve. This lifting-screw is operated through gears G which are driven from a shaft L that vertically extends through the post A³ and 60 drives motion from a shaft K extending transversely through the lower end A of said post. These gears are thrown in and out by conventional mechanism which includes 65 a shaft N (journaled at its upper and lower

ends in bosses 21 and 22) operated by a suitable hand-lever. The arm M is clamped by means of levers n and n' adapted to constrict the clamp lugs m and m'; these lever portions 8 being adapted to interlock with the 70 shaft N to hold it in its non-lifting position whenever the levers n and n' are functioning to clamp the arm, and conversely.

It will be seen that, by this arrangement, the various clamping-levers are at all times 75 immediately accessible to the user of the machine who is not obliged to shift his position for the purpose of locking the arm against either lateral or vertical movement, or both. Also, that the sleeve-clamping lever, by reason of the lug 18, may be operated with safety when the user is standing on a box or a step-ladder for the purpose of adjusting the machine for drilling large 80 castings. The levers, being arranged to remain in clustered relation, will be immediately accessible to the user even when limited in his position by his temporary support and, even though the nuts 6 had not been adjusted to take up undue slack in the sleeve-clamp (as it should be from time to time) the lever R could not swing farther than the user expected and thereby cause him to lose his balance and perhaps become injured 85 by falling.

Having thus revealed this invention, I claim as new and desire to secure the following combinations and elements, or equivalents thereof, by Letters Patent of the United States:—

1. A radial-drill combining a post; a sleeve pivoted thereto; an arm vertically adjustable on said sleeve; a clamp for locking said sleeve to said post; a clamp for locking said arm to said sleeve; hand-levers for actuating said arm-clamp; an upright shaft operatively connected with said sleeve clamp; a bearing bracket secured upon said arm; a bearing sleeve journaled in said bearing bracket and having a spline connection with said shaft; and a hand-lever fixed to said bearing sleeve and having its free end adjacent said arm clamping levers for manually actuating said sleeve clamp. 105
2. In a radial-drill in combination a post; a sleeve pivoted thereto; an arm vertically adjustable on said sleeve; a clamp for locking said sleeve to said post; manually actuatable means for actuating said clamp, said means comprising a shaft journaled in said sleeve and having one end operatively connected to said clamp; a bearing sleeve splined to said shaft, said bearing sleeve being formed with an external cylindrical bearing surface and an enlarged head affording a stop-shoulder; a bearing-bracket secured upon said vertically adjustable arm within which said bearing sleeve is journaled, said bearing-sleeve being greater in 110 length than the thickness of said bracket 120
3. In a radial-drill in combination a post; a sleeve pivoted thereto; an arm vertically adjustable on said sleeve; a clamp for locking said sleeve to said post; a bearing sleeve journaled in said sleeve and having one end operatively connected to said clamp; a bearing bracket secured upon said arm within which said bearing sleeve is journaled, said bearing-sleeve being greater in 125 length than the thickness of said bracket 130

and adapted to project therethrough when the stop-shoulder is in contact with said bracket; a hand-lever secured upon the projecting portion of said bearing-sleeve and affording means for rotating said sleeve and shaft to actuate said sleeve-clamp; and a stop for limiting the movement of said hand-lever.

In witness whereof, I hereunto subscribe my name, as attested by the two subscribing ¹⁰ witnesses.

DAVID C. KLAUSMEYER.
